United States Patent Office

Des. 192,954
Patented June 5, 1962

192,954

BRAID OR SIMILAR ARTICLE

Inge Petsche, Old Greenwich, Conn., assignor to The Bar-men Lace Corporation, Stamford, Conn., a corporation of New York

Filed Sept. 19, 1961, Ser. No. 66,753

Term of patent 3½ years

(Cl. D3—32)

FIG. 1 is a plan view of a braid or similar article, embodying my new design.

FIG. 2 is a side elevational view thereof.

I claim:

The ornamental design for a braid or similar article, substantially as shown.

References Cited in the file of this patent

UNITED STATES PATENTS

D. 104,778	Heim	-----	June 1, 1937
D. 125,358	Uziel	-----	Feb. 18, 1941
D. 138,944	Rosenbaum	-----	Sept. 26, 1944
D. 158,161	Wackerman	-----	Apr. 11, 1950

OTHER REFERENCES

Lingerie Merchandising, March 1957, page 59, floral lace and stripe fabric, bottom center of page.